DESIGN FOR AN AIR CONDITIONING VAPORIZER

Harry Goodman and Vachel S. Dillingham, Oklahoma City, Okla. assignors to R. M. Wolfe, Oklahoma City, Okla.

Application August 26, 1939, Serial No. 86,902

Term of patent 14 years

To all whom it may concern:

Be it known that we, Harry Goodman and Vachel S. Dillingham, residing at Oklahoma City, in the county of Oklahoma and State of Oklahoma, have invented a new, original, and ornamental Design for an Air Conditioning Vaporizer, of which the following is a specification, reference being had to the accompanying drawing, forming a part thereof.

Figure 1 is a top plan view of an air conditioning vaporizer illustrating our new design;

Figure 2 is a side elevation of the same unit;
Figure 3 is an end elevation of the same unit;
and,

Figure 4 is a perspective view of the same unit. The appearance of the opposite side of the device is substantially the same as the side shown. The rear of the device is substantially plain.

The distinctive feature of the design is the trough at one end of the unit.

We claim:

The ornamental design for an air conditioning vaporizer, as shown and described.

HARRY GOODMAN.
